CAN CARRIER

Frederic D. Empkie, Jr., Sioux City, Iowa, assignor to Container Corporation of America, Chicago, Ill., a corporation of Delaware

Application August 24, 1950, Serial No. 181,275

2 Claims. (Cl. 224—45)

1

The present invention relates to a can carrier, formed of foldable sheet material, having an integral upwardly extending handle portion, and refers particularly to means for permitting the handle portion to be folded over substantially parallel to the top of the carrier without impairing the subsequent efficiency of the carrier.

One of the objects of this invention is the provision of a can carrier of the type referred to which can be formed from a single blank of paperboard suitably creased and cut so that the parts may be secured by adhesive and staples, or other securing means, to produce the finished carriers in flat, collapsed form ready for delivery to a user. Another object of the invention is to secure the handle of the carrier in such a manner that after the carriers are filled with cans or similar articles they may be packed into larger cartons, or in any desired manner, with the handles folded substantially flat against the top of the carrier, and sufficient freedom of movement of the handle is allowed to prevent tearing of the carrier at the stapled portion of the handle.

Other and further objects and advantages of the invention will become apparent upon reading the following description, taken in conjunction with the accompanying drawings, showing a preferred illustrative embodiment of the invention, in which:

Fig. 1 is a perspective view of a can carrier embodying the present invention illustrating the carrier in assembled position ready to receive the cans for which it is designed;

Fig. 2 is a fragmentary perspective view of the can carrier with one end can in position in the carrier;

Fig. 3 is a cross sectional view, taken along the line 3—3 of Fig. 2;

Fig. 4 is a fragmentary perspective view of the can carrier partially disassembled and showing the partition element released from the handle portions and displaced downwardly;

Fig. 5 is a cross sectional view, taken along the line 5—5 of Fig. 2;

Fig. 6 is a fragmentary perspective view showing a plurality of the can carriers embodying the present invention as they are packed into a large container with the carrying handles folded substantially flat against the tops of the carriers;

Fig. 7 is a fragmentary cross sectional view of the carrying handle folded flat against the top of the can carrier illustrating the slippage between the partition and the handle forming flanges; and

Fig. 8 is a plan view of a preferred form of

2

the blank from which the can carrier embodying the invention is manufactured.

The can carrier of the present invention is preferably formed to provide a convenient carry-out for a retail store customer to take some six or more cans of beverage or food, and is particularly designed so that the filled carriers may be packed in shipping containers for transportation from the packer to the wholesaler, jobber or retailer. The carrier is made with a carrying handle that may be folded flat against the filled carrier, and a centrally disposed reinforcing partition extending between the flanges forming the handle is particularly designed to permit the partition to slip relative to the handle flanges when the handle is folded. This relative slippage between the partition and the handle flanges protects the partition against being torn by the staples or other fastening elements securing the flanges together to form the handle when the handle is folded.

Referring more particularly to Fig. 1 of the drawings, the carrier as herein disclosed comprises a pair of horizontal bottom wall panels 2 and 3, vertical side wall panels 4 and 5, horizontal top wall panels 6 and 7, vertically extending handle forming flanges 8 and 9, a centrally disposed, vertically extending partition 10, and a glue flap 11.

The horizontal bottom wall panels are each formed with a pair of arcuate cut-out tabs 12 and 13 which are folded upwardly out of the panels through an angle of approximately 180° so as to underlie cans inserted into the carrier and engage the inner radius of the flanges of the outer cans to prevent accidental lateral displacement of the cans after they have been positioned in the carrier. The edges of the top flanges of the outer cans are similarly engaged by tabs 14 and 15 formed by folding the end portions of horizontal top wall panels 6 and 7 downwardly and inwardly along score lines provided for the purpose.

The carrying handle is formed by the flanges 8 and 9 which are folded downwardly along the fold line 16. The upper portion 17 of the centrally disposed vertical partition 10 is positioned between the flanges 8 and 9 to form a reinforcement for the handle. A plurality of staples or similar fastening elements 18 is driven through the flanges 8 and 9 to secure them together tightly so that when the handle is folded downwardly against the top of the carrier the flanges move as a single unit. The staples may be positioned anywhere above the fold lines 19 and 20 which

connect the flange 8 to the horizontal top wall panel 6 and the flange 9 to the panel 7, respectively, but are preferably positioned immediately adjacent the fold lines 19 and 20.

When a plurality of filled carriers is transported from the packer to the retailer it is desirable to load them into shipping containers 21, as shown in Fig. 6, and the handles of the individual carriers are preferably folded over against the top of the carriers to save packing space. The carriers may be shipped to the retailer, if desired, in collapsed condition and filled by the retailer so that loading of the filled carriers in shipping containers is unnecessary. However, even under these conditions some retailers may desire to fill a quantity of carriers and stack them so that the handles are folded against the top of the carriers. When the handle is folded downwardly against the top of the carrier the fold lines 19 and 20, and the fold lines between the side wall panels and the top panels, permit the flanges 8 and 9 to move in either direction without binding. The portion 17 of partition 10, however, is relatively fixed at its bottom edge because the cans hold the bottom wall panels 2 and 3 rigidly. The lower edge of partition 10 is connected to panel 2 by a fold line 22 and to panel 3 by the glue flap 11 to which it is adhered. Consequently the upper portion 17 of the partition can not move with the same freedom as flanges 8 and 9.

In order to permit the upper portion 17 of the partition to be folded with the flanges 8 and 9 without causing the partition to be torn by the staples 18 or similar fastening elements, an aperture 23 is formed in the portion 17 of the partition in alignment with the place where each staple 18 is to be driven. The apertures 23 are each longer than the staple, and are wide enough to permit the staples to secure the flanges together without penetrating the material of the portion 17 of the partition. When the carrier handle is in upright position the staples 18 are positioned approximately centrally of the apertures 23, as shown in Fig. 5. When the handle is folded out of its vertical plane the partition 10 is folded around a pivot formed by the lower edge of either flange 8 or 9 and the inner edge of the adjacent top wall panel 6 or 7. As the handle is folded along fold lines 19 or 20, respectively, the upper portion 17 of partition 10 must move a greater distance than the flanges 8 and 9 because the lower portion of partition 10 is relatively fixed, and, consequently, as shown in Fig. 7, the upper portion 17 moves relatively to the flanges 8 and 9. Such movement would cause the staples 18 to tear the partition 10 if the partition was secured firmly to the flanges 8 and 9 by the staples. The upper portion 17 of the partition due to the provision of the apertures 23 is thus enabled to move relatively to the flanges 8 and 9 which eliminates the possibility of tearing the partition by the staples.

To facilitate carrying the filled carrier the flanges 8 and 9 are preferably provided with partially cut out tabs 24 and 25 which may be folded to form a hand hold. The upper portion 17 of partition 10 is preferably provided with an opening 26 to register with the opening formed by folding the tabs 24 and 25.

While the present description sets forth a preferred embodiment of the invention, certain changes may be made in the construction without departing from the spirit of the invention, and it is therefore desired that the present embodi-

ment be considered in all respects as illustrative and not descriptive, reference being had to the appended claims rather than to the foregoing description to indicate the scope of the invention.

5 I claim:

1. A can carrier composed of material such as paperboard and comprising, a pair of parallel can receiving compartments separated by a centrally disposed partition and a top wall over each 10 compartment, the inner edges of the top walls terminating adjacent to the opposite faces of said partition, a pair of handle flanges, one extending upwardly from each of the inner edges of said top walls and being joined to the respective top walls along score lines substantially parallel to one another and being foldable together about said score lines from a position where they extend substantially vertical to the planes of the top wall to a position where planes of the flanges 20 and the planes of the top walls are parallel, said handle flanges having a height not exceeding the distance from the central partition to the side wall, the said partition having a handle reinforcing portion hinged to the partition along its upper end on a line adjacent and parallel to the handle flange score lines and extending upwardly between said upwardly extending handle flanges for reinforcement of the handle, fastening means passing through and between said 30 handle flanges for relatively permanently securing the same together, said partition portion being formed with a pair of spaced openings located above the hinge line connecting the handle reinforcing portion and each including a downwardly facing edge overlying and in spaced relation to said fastening means, said partition portion and said edges being relatively freely movable downward and upward between predetermined limits and between said handle flanges 35 relative to said fastening means, whereby said handle flanges are secured together and said partition portion is disposed therebetween without direct penetrating engagement by said securing means and whereby said handle may be folded 40 into parallel relation with respect to said top walls without tearing said partition portion.

2. A can carrier of the character described comprising, a single integral length of material such as paperboard, cut, scored and folded to 50 provide a bottom wall, a top wall, opposite side walls connecting the bottom and top walls in spaced relation to one another, a partition member extending upwardly medially of said bottom wall to a place medially of said top wall and in 55 a plane generally parallel to the planes of said side walls, a pair of parallel handle-forming flanges disposed and projecting upwardly from and medially of said top wall and having their planes substantially parallel to the plane of said 60 partition the said flanges having hinged connection with said top wall along parallel score lines for movements together from said position parallel to said partition to a position substantially parallel to said top wall, said partition having a 65 handle-reinforcing portion hinged thereto along its upper end on a line adjacent and parallel to said flange score lines and projecting upwardly between said flanges, said handle-reinforcing portion having a pair of downwardly facing edges 70 disposed in spaced relation to one another and lying within the areas of the adjacent faces of said flanges, and securing means such as staples passing through said flanges out of contact with said reinforcing portion of said partition and adjacent to and spaced from said downwardly fac-

ing edges and in the path of movement of said edges on movement of said reenforcing portion downward in a vertical direction relatively to said flanges when said flanges and reenforcing portion are swung together about said score lines to said position paralleling said top wall, said bottom, top and side walls and said central partition forming a pair of compartments adapted to receive two sets of cans confined within the space between the top and bottom walls, and said handle flanges having a height not exceeding the distance between the central partition and the side wall.
